UNITED STATES PATENT OFFICE

2,448,779

SWITCH MECHANISM FOR AUTOMATIC STOKERS

George W. Crise, Columbus, Ohio

Application December 8, 1945, Serial No. 633,815

6 Claims. (Cl. 200—19)

1

My invention relates to temperature control switches of the type incorporating a timing mechanism in governing the operation thereof. More specifically, it relates to temperature control switches used for controlling automatically the operation of fuel stokers for furnaces.

In furnaces of this type, it is necessary that the stoker be driven at definite intervals so as to provide sustained combustion of fuel in the furnace. In relatively mild weather, it is a matter of common occurrence that the operative circuit controlling the motor employed in driving the blower and fuel-feeding auger of a standard stoker is not closed under the automatic control of the thermostatic switch at intervals of time spaced sufficiently close to insure a sustained low-fire condition of operation.

To avoid this condition, it is an object of my invention to provide a thermostatic switch whose operating circuit is closed at time-regulated intervals independent of thermostatic action, whereby to assure adequate combustion of the fuel.

Another object of my invention is to provide a time-regulated thermostatic switch whose operating life is greatly extended by the elimination of wearing parts within the time-driven mechanism.

For a further understanding of the invention, reference is to be had to the following description and the accompanying drawings, wherein:

Fig. 1 is a diagrammatic view disclosing my improved switch mechanism for temperature-controlling apparatus;

Fig. 2 is a side elevational view partly in vertical section of the chronometer switch;

Fig. 3 is a detailed vertical-sectional view taken along the line 3—3 of Fig. 1;

Fig. 4 is a perspective view of the two magnets contained in the chronometric switch.

Referring to Fig. 1 of the drawings, my temperature-control switch comprises a synchronous motor 5, speed reducing gears 6 driven by the motor 5, a rotating cam 7 connected with, and driven at a relatively slow speed by the gears 6, a thermostat 8 having normally spaced contacts 9 and 10 which upon engagement close an operating circuit, an adjustment arm 11 for the thermostat 8 actuated by the rotating cam 7 so as to vary the spacing between the contacts 9 and 10 independent of thermostatic action, and a chronometric switch 12 electrically connected to the operating circuit of the thermostat 8 and

serving by its action to close the operating circuit independent of the thermostat 8.

Referring to Fig. 2 of the drawings, the chronometric switch 12 comprises a base 13, a rotating gear 14, a magnet 15 radially mounted and movable on the rotating gear 14, a set screw 16 incorporating a time-calibrated scale and directly connected with the magnet 15, thereby serving to rotate the magnet 15 on the gear 14 causing a circular displacement of its magnetic field, a second magnet 17 having a resilient supporting arm 18 and movable toward the magnet 15 when in registration therewith, and a pair of contact terminals 19 and 20, said terminal 19 being rigidly attached to the supporting arm 18 is adapted for engagement with the terminal 20 when the magnets 15 and 17 are in registration with each other.

In the operation of the chronometric switch 12, the rotating gear 14 is driven at a given rate of speed, such as one revolution per hour, by the synchronous rotor 5. Thus, the magnet 15, attached to the rotating gear 14, is brought in direct registration with the second magnet 17 for a short period of time during each revolution.

Referring to Fig. 4 of the drawings, the magnets 15 and 17 are so situated, when in registration with each other, as to cause an attraction between the two. The magnet 15 is connected directly to the set screw 16 so that when the set screw 16 is rotated there is a circular displacement of the magnetic poles of magnet 15, thereby causing a varying degree of attraction between the magnets 15 and 17, resulting in a shortening or lengthening of the period of attraction between the two. When the magnets 15 and 17 are in registration with each other, the magnet 17, having a resilient supporting arm 18, moves toward the magnet 15, thereby engaging the contact terminals 19 and 20 and closing the operating circuit of the switch.

Referring to Fig. 3 of the drawings, in operation the cam 7, comprising a node 21 and a dwell 22, is rotated at a relatively slow speed, such as one revolution per twenty-four hours, by the speed reducing gears 6. The adjustment arm 11 of the thermostat 8 is held by spring tension against the circumference of the cam 7, and is subject to circular displacement by the node 21 when the cam 7 is rotated. The displacement of the adjustment arm 11 in turn, causing a variance in the spacing of the contacts 9 and 10 independent of the action of the thermostat 8.

55 In view of the foregoing, it will be manifest

that the present invention provides a time-regulated switch for opening and closing the operating circuit of an automatic coal-feeding stoker at definite intervals, and in a manner independently of the usual control for such a circuit afforded by the thermostatic switch. The construction is characterized by its structural simplicity, manufacturing economy and operational reliability. The switch functions automatically and requires but little or no manual attention after the same has been properly adjusted to meet operating conditions. It will be understood that the construction disclosed is exemplary of but one of the embodiments of the invention, therefore, the same is subject to certain modifications without departing from the scope of the following claims.

I claim:

1. In a mechanism of the character described, a time-operated switch comprising a rotatable element driven by chronometric motor means, an adjustable magnet attached to said rotatable element and movable thereon so as to cause a circular displacement of its magnetic field, a second magnet in spaced longitudinal relationship with the circumference of said rotatable element and having a resilient supporting body, and a pair of oppositely disposed contact terminals having an operating circuit, one of said contact terminals being rigidly attached to and movable with the resilient supporting body of the second magnet.

2. In a mechanism of the character described, a time-operated switch comprising a driven rotatable element having an adjustable magnet radially mounted thereon, a chronometric means for driving said element, a time-calibrated adjustment means mounted on said rotatable element in relation to said adjustable magnet so as to vary the displacement of its magnetic field, a second magnet in spaced longitudinal relationship with the circumference of said rotatable element and having a resilient supporting body, and a pair of oppositely disposed contact terminals, one of the latter being rigidly attached to and movable with the resilient supporting body of the second magnet.

3. In a timing switch, a movable primary magnet traversing a fixed path of travel, a second magnet positioned near said path of travel and

influenced by the passing of said primary magnet, a contactor operable by one of said magnets when the same is under the influence of the other magnet, and adjustable means for rotating one of said magnets on its axis whereby the mutual attraction between the magnets may be altered.

4. In a magnetically operated switch, cooperating magnetic elements, a contactor operable by one of said elements, means for moving one element toward and from the other to cause operation of the contactor, and adjusting means for changing the maximum mutual attraction between the elements, said means including a rotatable mounting for adjustably turning one of the magnetic elements.

5. In a magnetically operated switch, a pair of normally spaced cooperative magnetic elements, a yieldably mounted contact operable by the movement of one of said elements, a second contact, means for moving one of said elements into sufficient proximity to the other element so that the magnetic attraction between the elements will move the yieldably mounted contact into operable engagement with the second contact, and means for adjustably rotating one of the magnetic elements, whereby the distance between the magnetic elements will cause a greater or lesser attraction between said elements.

6. In a magnetically operated switch as defined in claim 5 and wherein the means for rotating one of the magnetic elements has associated therewith an adjustment-indicating means.

GEORGE W. CRISE.
